H. H. YERK

ROTARY ICE BREAKING MACHINE

Filed Nov. 29; 1922

TIG. 2.

75

FIG. 5.

Henry H. York Inventor

Lloyd L. Evans

Attorney

UNITED STATES PATENT OFFICE.

HENRY H. YERK, OF DAVENPORT, IOWA, ASSIGNOR TO MICRO MACHINE COMPANY,
OF BETTENDORF, IOWA, A CORPORATION OF IOWA.

ROTARY ICE-BREAKING MACHINE.

Application filed November 29, 1922. Serial No. 603,933.

To all whom it may concern:

Be it known that I, HENRY H. YERK, a citizen of the United States, residing at Davenport, in the county of Scott and State 5 of Iowa, have invented a certain new and useful Improvement in Rotary Ice-Breaking Machines, of which the following is a full, clear, and exact description, reference being had to the accompanying drawings.

10 This invention relates to ice breaking machines and more particularly to those of the type in which a rotary toothed drum within a hopper cooperates with a fixed grate or comb having teeth between which the cylinder teeth pass. It is common practice with such machines to furnish a plurality of grates, such grates having different numbers of teeth thereon to provide different sizes of ice such as coarse, medium and fine.

15 It is an object of the present invention to provide means whereby one grate bar can be quickly replaced by another, the latter having either differently spaced teeth to obtain different sizes of broken ice, or the same number of teeth so that if one or more teeth of one grate is broken another grate can be supplied with a minimum loss of time and without tying up the machine until an additional bar can be secured from the 20 factory.

25 A further object is to provide an interchangeable grate structure in which a series of grate bars with spaced teeth can be brought into operative position with respect to the drum and which are adapted to be rigidly held in such position.

30 Another object of the invention is to provide a simple and efficient means for selectively changing and clamping any of the 40 various grate bars into operative position.

35 A further object is to provide an interchangeable grate structure in which escape of ice through the hopper wall is prevented.

40 Other objects will be apparent from the 45 following description and annexed drawings.

50 The following description and annexed drawings set forth in detail certain means embodying my invention, the disclosed means, however, constituting but one of the various mechanical forms in which the principle of the invention may be employed.

Reference should be had to the annexed drawings forming a part of this specification in which:

55

Figure 1 is a side elevation of the machine partly in section.

Fig. 2 is a front elevation of the machine.

Fig. 3 is a fragmentary perspective view of the shaft and operating mechanism on 60 which the grate bars are mounted.

In the accompanying drawings it will be seen that the ice breaking machine consists of a hopper 1 in which is mounted a cylinder 2 with teeth 3 detachably secured thereto, 65 the cylinder being driven in any suitable manner from a source of power, there being shown in the drawing a wheel 4 for receiving a belt, though it is to be understood that it can be driven from a motor through 70 gearing. The side wall 5 of the hopper 1 toward which the upper part of the cylinder turns has a transverse rectangular slot 6 therein somewhat below the axis of the cylinder through which the grate teeth carried by a bar on the outside of the hopper project.

75 In order to provide means for quickly changing the grate bars, a shaft 7 outside the hopper 1 is carried by the arms 8 pivoted 80 at 9 to the end walls 10 of the hopper. The shaft 7 is formed polygonal in cross section intermediate its ends to furnish flat faces 12 to which are secured grate bars 14, 15, 16. These bars have teeth 13 thereon and the 85 latter may be differently spaced on each of the bars for coarse, medium and fine cutting respectively. Or if a user of this machine desires to cut only one size of ice, the bars 14, 15, 16 may carry the same number 90 of teeth and the additional bars be used for replacing worn or broken grate bars.

95 In order to hold any one of the bars in operative position with the teeth projecting through the slot 6 of the machine, the pivot arms 8 are clamped to the machine by any suitable clamp such as the clamps 17 which are pivoted at 18 to the brackets 19 carried by the machine. When the arms 8 are swung upwardly and clamped in position 100 one of the flat faces 12 of the shaft 7 is presented toward the slot 6 and the grate bar secured to such face 12 is held tightly against the rear face of the hopper with its

teeth 13 projecting into the hopper. The clamps 20 may be operated to engage the recesses 21 in the arms 8 to prevent disengagement during the operation of the machine. Also, the lower ends of the arms 8 may be connected by a bar 24 to make the arms more rigid and to insure that they move together when swung about the pivots 9. The bar 24 may be threaded at its ends and carry nuts 25 therein to engage the opposing faces of the arms 8, so that they may be properly spaced and adjusted laterally.

When it is desired to change the grate bars it is only necessary to unscrew the members 20 so that they can be swung free of the slots 21. The arms 8 carrying the shaft 7 will then swing on the pivots 9 until the stops 23 at the lower ends of the arms engage the inclined wall 5 of the machine. In this position the shaft 7 can be rotated to present any of the flat faces with its grate bar toward the slot and the arms moved back and clamped in place with the clamps 17 as previously described.

It is to be understood, however, that if desired the shaft 7 and grate bars may be cast integrally and operated in the same manner to bring the teeth into operative position as heretofore described. In this case one sacrifices the feature of interchangeability of grate bars for simplicity of having them all integral.

It will be seen that the faces of the grate bars 14, 15, and 16 are each of a width and length to completely cover the slot 6 so that there is no leakage of ice through the slot during the operation of the machine. The bodily movement of the rotary shaft 7 permits the rotary adjustment thereof without enlarging the slot in the hopper to permit rotation of the tooth carrier and makes it possible to obtain the advantages of rotary adjustment without the disadvantage of openings in the hopper wall through which broken ice may escape. Also, the adjustable clamps at the ends of the arms 8 serve to tightly clamp any one of the grate bars in place and permit quick interchanging of the bars.

It will also be noticed that the weight of the shaft 7 and the grate bars is carried by the arms 8 and that these parallel arms permit the grate bar to move bodily outwardly away from the slot until the shaft 7 is in position where it can be rotated to present any of the grate bars toward the hopper. The outward movement of the arms 8 is stopped by the lower ends of the arms engaging the walls of the machine and thus the shaft 7 with the flat faces 12 will be supported in position for easily detaching any of the grate bars from one of the faces or attaching a grate bar thereto. Furthermore, it is to be understood that

the particular forms of apparatus shown and described, and the particular procedure set forth, are presented for purposes of explanation and illustration and that various modifications of said apparatus and procedure can be made without departing from my invention as defined in the appended claims.

What I claim is:

1. In an ice breaker, the combination with a hopper having a rotary toothed cylinder therein and a slot in a wall thereof alongside the cylinder, of a grate bar having a face portion rigidly but detachably clamped against the outer face of the hopper, the face of said grate bar being of a sufficient width and length to cover said slot and engage the wall of the hopper surrounding the slot, said bar having spaced teeth projecting through said slot. 75 80 85

2. In an ice breaker, the combination with a hopper, having a rotary toothed cylinder therein and a slot in the front wall thereof alongside the cylinder, of a grate bar having a face portion adapted to be clamped against the wall of the hopper on the outside thereof, said face portion of the bar completely covering said opening and engaging the edge of the wall surrounding the slot, said bar having teeth projecting through said opening, and means for clamping said grate bar in position. 90 95

3. In an ice breaker the combination with a hopper having a rotary toothed cylinder therein and a slot in its wall alongside said cylinder, of a shaft having a plurality of faces, said shaft being rotatably mounted outside said hopper alongside the slot, said shaft having teeth mounted on the faces thereof adapted to project through the slot in the hopper wall, and means for clamping said shaft with a face in engagement with said hopper wall, said clamping means being releasable to permit the bar to move outwardly sufficiently to 100 105 110 permit rotation thereof.

4. In an ice breaker, the combination with a hopper having a rotary toothed cylinder therein and a slot in its wall alongside the cylinder, of a plurality of grate bars rotatably mounted and having teeth on their faces adapted to project through the slot, the faces of said bars being of a width and length to completely cover said slot and means for securing one of such faces thereof against the wall of the hopper outside the slot. 115 120

5. In an ice breaker, the combination with a hopper having a rotary toothed cylinder therein and a slot in a wall thereof alongside the cylinder, of a rotatable shaft carrying a plurality of grate bars with teeth projecting from the faces thereof, said shaft being swingably mounted, and clamping means connected to said shaft mounting and 125 130

hopper whereby one of said bars may be held with its face tightly against the wall of said hopper adjacent said slot.

6. In an ice breaker, the combination with a hopper having a rotary toothed cylinder therein and a slot in its wall alongside the cylinder, of a rotatably mounted shaft outside the hopper for movement toward and from said slot, said shaft completely covering said slot when in operative position, and a plurality of circumferentially spaced rows of teeth upon said shaft.

7. In an ice breaker, the combination with a rotary toothed cylinder, of a wall adjacent the cylinder having a slot alongside the cylinder, a rotary shaft on the outer side of the wall carrying differently spaced sets of teeth adapted to be inserted through said slot, said shaft being adjustable bodily away from said wall to clear the teeth thereof to permit rotation, and means for clamping said shaft in operative position.

8. In an ice breaker, the combination with a hopper having a rotary toothed cylinder therein and a slot in its wall alongside the said cylinder, of pivoted arms mounted outside the hopper for movement toward and from said slot, a rotatable shaft carried by said arms, said shaft having faces carrying a plurality of spaced rows of teeth thereon to be projected selectively into said slot.

9. In an ice breaker, the combination with

a hopper having a rotary toothed cylinder therein and a slot in the wall of the hopper, of arms pivoted to the frame of the machine, a rotatable shaft carried by said arms, a plurality of grate bars carried by said shaft, means for clamping said arms to hold one of said grate bars tightly against the wall of the hopper adjacent said slot and means to stop the movement of said arms away from said hopper when said clamping means is inoperative to hold said shaft and bars for adjustment.

10. In an ice breaking machine the combination with a hopper having a rotatable drum therein and a slot in the wall of the hopper, of arms pivoted to the frame of the ice breaking machine for movement toward and from the machine, a rotatable shaft mounted in said arms, a plurality of series of teeth secured to said shaft and adapted to be selectively projected into said hopper when said shaft is held in operating position, means for clamping said arm to hold said shaft inwardly, means to cause said arms to move outwardly in parallelism to bodily move said shaft and means to stop the movement of said arms when the shaft has been moved outwardly.

In testimony whereof, I hereunto affix my signature.

HENRY H. YERK.
